UNITED STATES PATENT OFFICE.

VICTOR WILLOUGHBY, OF JEFFERSONVILLE, INDIANA, ASSIGNOR TO AMERICAN CAR
AND FOUNDRY COMPANY, OF ST. LOUIS, MISSOURI, A CORPORATION OF MISSOURI.

DRAFT-GEAR.

1,122,454.

Specification of Letters Patent. Patented Dec. 29, 1914.

Application filed April 27, 1912. Serial No. 693,695.

To all whom it may concern:

Be it known that I, Victor Willoughby, residing at Jeffersonville, Clark county, Indiana, and being a citizen of the United States, have invented certain new and useful Improvements in Draft-Gear, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 represents a plan view of a draft gear constructed in accordance with this invention partially broken away taken on the line 1—1 of Fig. 2, looking in the direction of the arrow. Fig. 2 represents a rear view of the draft gear partially in section taken on the line 2—2 of Fig. 1, looking in the direction of the arrow. Fig. 3 represents a side view of the draft gear partially in section taken on the line 3—3 of Fig. 2.

This invention relates to shock absorbing means for drawbar draft rigging for car couplers, and comprehends in its adaptation suitable means for compressing and distorting the draft springs and the utilization of friction between the operative parts.

It also comprehends in its adaptation the employment of a rear follower container for the compensating or shock absorbing elements, so arranged that all of the shocks shall be absorbed internally of the device.

Referring to the drawings illustrating this invention, the accepted construction of yoke 4 is employed, and is provided with the usual shoulders 5 and bolt holes 6 for securing the drawbar, which is not shown in the drawings, and the said yoke is adapted to embrace the passive elements of the draft rigging, which consist of a front follower plate 7 and a container rear follower 8 that is provided with inclined side walls 8^a and with reinforcing or stiffening webs 8^b, and forms a part of a pocket for the draft springs 9 and 9^a. The front follower plate is provided with a projection 7^a forming a front bearing for the draft springs, and is also provided with a shoulder 7^b.

The compensating or shock absorbing elements of the draft rigging comprise a pair of wedges 10 shaped to conform to a portion of the draft springs, and comprising with the container rear follower the draft spring pocket. These wedges, as their name implies, are provided with inclined outer surfaces conforming relatively to the inner inclined surfaces 8^a of the container rear follower, and the bases of the wedges are provided with projecting shoulders 10^a abutting and overlapping the shoulders 7^b of the front follower projection. While these shoulders abut and overlap, a sufficient play is permitted to provide for a sliding play of the wedges as they travel on the inclined wall 8^a of the container rear follower 8. The device is adapted to be employed in M. C. B. construction, and, therefore, the draft sills and front and rear follower stops are shown in dotted lines.

The operation of this device is very simple, as for example, a buffing shock is to be compensated, the forward active element, the drawbar base being in direct abutment with the passive element, the front follower 7, the front follower is forced backward until it abuts the shoulders 10^a of the wedges 10; in the meantime the projection 7^a of the front follower 7 has compressed the draft springs 9 and 9^a, and the wedges 10 moving backward on the inclined surfaces 8^a of the container rear follower 8 gradually constrict the spring pocket, distorting or twisting the draft springs into an irregular or unnatural shape, thereby utilizing the compression of the springs and the distortion of the springs in addition to the friction caused by the backward wedging motion of the wedges upon the inclined surfaces of the container rear follower and quickly, yet gradually, compensating the buffing shock. The tension or pulling shock is compensated by the action of the yoke 4 upon the container rear follower moving the same forward and thereby compressing the draft springs against the front follower projection until the shoulders 10^a of the wedges abut or strike the front follower, and the operation of compensating this shock is analogous to the action of the parts under buffing shock. It will, therefore, be perceived that while the active element, the drawbar and yoke change under different shocks, the passive elements, the front and

2
rear followers and the compensating and shock absorbing elements, the wedges and springs, remain in the same relative operative relationship to each other and operate 5 the same, eliminating the jar consequent from vibration of the springs from activity to rest. The resiliency of the draft springs is only utilized to maintain the normal relationship of the parts.

10. What I claim is:

1. In a draft gear construction, sills and stops, a front follower and a container rear follower and draft spring distortion elements normally spaced from the front follower and operated longitudinally and laterally by the front follower and within the container rear follower, said spring distortion elements being subsequently engaged by said front follower to limit the relative 15 movement between the latter and said friction elements in one direction.
2. In a draft gear, a draw bar and yoke, front and rear followers, draft springs embraced by the said yoke, and friction elements normally spaced from the front follower 20 and embraced by the rear follower adapted to distort said draft springs and to subsequently engage said front follower to have their forward movement arrested under draft strain.
3. In a draft gear, a draw bar, a yoke and draft springs, a front follower, a container rear follower provided with tapered inner side walls, a pair of friction wedges oper- 25 atively connected with said front follower, partly embracing one of said springs and operating within the container rear follower against the tapered inner walls thereof and adapted to move together radially of the draft springs and thereby distort the latter, said springs engaging the rear follower and means rigid with the front follower.
4. In a draft gear, a pair of co-acting 30 springs one within the other, a front follower and a container rear follower engaging said springs, said front follower having a portion adapted to be projected into said rear follower, longitudinally and laterally

movable friction and spring distortion elements acting within the container rear follower and upon the draft springs to distort the same said springs engaging both the front and rear followers.

5. In a draft gear, a draw bar and yoke, a front follower abutting the draw bar, a container rear follower abutting the yoke and nested springs engaging both the front and rear followers and friction elements within the container rear follower surrounding said 60 springs and adapted to contract the draft spring cavity and distort said springs, said friction elements being rendered effective in both directions by said front follower.

6. In a draft gear construction, a rear follower including forwardly projecting members forming a housing, said members each having an inclined inner wall, a front follower, a spring abutting both front and rear followers, a pair of oppositely disposed 65 wedges, each having an inner face conforming to the conformation of and engaging a side of said spring and an outer inclined face engaging one of said inclined walls.

7. In a draft gear, draft springs, a front follower, a container rear follower provided with tapered inside walls and with reinforcements on the outside thereof, a pair of wedges operating against the tapered inside walls of said container, the followers and 70 said wedges forming within the rear follower a longitudinally and transversely contractible draft spring cavity within which the draft springs are adapted to be distorted by the contraction.

8. In a draft gear, a draw bar and a yoke, front and rear followers, a projection on the front follower, draft springs embraced by the said yoke, friction elements partially embracing the draft springs and projection 75 and embraced by the rear follower and adapted to distort said draft springs.

In witness whereof I have hereunto set my hand in the presence of two witnesses.

VICTOR WILLOUGHBY.
